UNITED STATES PATENT OFFICE.

PATRICK J. MOORE, OF SAN FRANCISCO, CALIFORNIA.

OIL-CAN.

SPECIFICATION forming part of Letters Patent No. 416,939, dated December 10, 1889.

Application filed November 7, 1888. Renewed September 23, 1889. Serial No. 324,828. (No model.)

To all whom it may concern:

Be it known that I, PATRICK J. MOORE, a citizen of the United States, residing in the city and county of San Francisco, and State 5 of California, have invented certain new and useful Improvements in Oil-Cans, of which the following is a specification.

My invention has for its object to secure free and ample vent and an even discharge 10 of oil at the nozzle, without possibility of overflow or escape at the vent under any condition of use; and to such end and purpose my invention consists in the construction and combination of parts as hereinafter fully described, producing an improved oil-can for 15 machinists and for general use as well.

I proceed to construct, apply, and carry out my invention as follows, the accompanying drawing being referred to by letters.

20 The figure illustrates an oil-can for engineers' use, having a long nozzle.

A represents the body of the can, and A^x its nozzle.

B is a tube that is carried up from the 25 lower part of the body near the bottom and out through the side, and is fixed in upright position either against the side of the can or at some little distance from the side, to leave room between the tube and the body for the 30 hand to be slipped in, which last-mentioned position forms a handle of the tube for lifting and using the can. The lower end of this tube leads out from the oil-holding space inside, and its top end is open to the air or 35 is closed by a suitable cap or stopper. A smaller tube C is carried out from a point below the top in an upward direction to a point

considerably higher, through which tube a free vent is obtained. This construction is particularly adapted for cans with long tapering nozzles—such as are used on locomotives and for oiling parts of machinery difficult of access—the tube B being employed, also, as a filling-inlet, and having its opening in the top closed by a cap or plug D. The 40 vent-tube C is brought out below the stopper, and is fixed against the side of the can and up along the side of the nozzle, so that it lies out of the way.

The form of can I have represented is well 45 adapted for all general purposes.

The top of the tube B is kept closed except when the can is to be filled.

A curved brace B' may be employed to connect the top of the tube B to the can, and a 50 similar brace C' may be employed between the can and the vent C.

Having thus fully described my invention, what I claim, and desire to secure by Letters Patent, is—

60 The combination, with a can having a spout, of a filling-tube B, forming the handle of the can and provided with a removable closing-piece D, and a vent-tube C, extending upward and out from the filling-tube above the 65 filling-aperture therein along the outside of the spout of the can, as set forth.

In testimony that I claim the foregoing I have hereunto set my hand and seal.

PATRICK J. MOORE. [L. S.]
